LOCKING MEANS FOR EXPANSIBLE
LOOSE-LEAF BINDERS

Ernest Hazel, Jr., St. Louis, Mo.

Application July 16, 1948, Serial No. 39,065

2 Claims. (Cl. 129—13)

1

This invention relates to binders and particularly those of the loose leaf type provided with a pair of operable back panels shiftable toward and away from each other for receiving various numbers of loose leaves, the primary object being to provide a simple, inexpensive and highly efficient locking means for holding the panels against outward movement when the leaves are disposed therebetween.

The most important object of this invention is to provide a locking means for expansible loose leaf binders having a tubular member joined to each of the panels respectively and disposed in relative telescoping relationship, said members being provided with interengageable structure therein for holding the same against movement in one direction.

A further object of this invention is to provide a pair of relatively telescoped members having manually operable locking means disposed therein for releasably holding the same against separation, said tubular members being adaptable for use with loose leaf binders as above set forth, for use as mounting posts for the paper itself, if desired; or usable separately without utilizing the above-mentioned panels for mounting and holding a sheaf of perforated paper.

Another important object of this invention is the provision of locking means for loose leaf binders of aforementioned character wherein one of the tubular members has a pair of opposed swingable dogs mounted therein and projectable from said one member into biting engagement with the other members that surround the dogs.

Other objects of this invention relate to the manner of normally releasing said locking dogs or posts; the way in which the swingable dogs are yieldably held in wedging relationship with respect to the two tubular members and to many other minor details of construction, all of which will be made clear during the course of the following specification, reference being had to the accompanying drawing, wherein:

Fig. 1 is an end elevational view of an expansible loose leaf binder showing one modification of locking means forming the subject matter of this invention, parts being broken away to reveal details of construction.

Fig. 2 is an enlarged fragmentary cross sectional view through the locking means, per se, taken on line II—II of Fig. 1.

Fig. 3 is a fragmentary transverse cross sectional view taken on line III—III of Fig. 2.

Fig. 4 is a cross sectional view similar to that illustrated in Fig. 3, showing another form of

mounting for the releasable dogs of the locking means; and,

Fig. 5 is a fragmentary cross sectional view similar to that shown in Fig. 2, showing another modification of the push-button portion of the locking means.

The locking means about to be described has been designed for use with many different types of conventional loose leaf binders and, therefore, the binder shown in the drawing is for illustrative purposes only.

This binder is broadly designated by the numeral 10 and constitutes a pair of back panels 12 and 14. These panels 12 and 14 are each normally L-shaped. The shorter legs 16 and 18, respectively, thereof being relatively overlapping as clearly indicated in Fig. 1. Lines of weakness 20 in both panels 12 and 14 present hinges for permitting swinging of the panels 12 and 14 to and from an open position in the usual manner. That portion of the panels 12 and 14 extending from hinge lines 20 to the legs 16 and/or 18 themselves is formed from relatively rigid material. Such material is indicated in Fig. 2 by the numeral 22 and layers of flexible material that cover the entire panels 12 and 14 are designated by the numeral 24.

The locking means, per se, forming the subject matter of Figs. 1 to 3, inclusive, of this invention is broadly designated by the numeral 26 and includes a pair of tubular members 28 and 30 having differing diameters. The tubular member 30, which is of the larger diameter, is secured directly to the panel 14 by passing through an opening 32 formed therein. An out-turned shoulder 34 formed in the tubular member 30, spaced inwardly from one end thereof, rests against the innermost face of the panel 14 and an out-turned flange 36 bearing against the outermost face of panel 14 holds this member rigidly in place.

The tubular member 28 is telescoped within the tubular member 30 by passing through an opening 38 formed in the uppermost end of member 30, opposite to the flange 36 thereof. The diameter of this opening 38 is substantially the same as the outside diameter of member 28, presenting a relatively tight sliding fit between member 28 and member 30.

Consequently, the outermost face of the smaller member 28 is spaced from the inner walls of the tubular member 30.

Member 28 has an out-turned rib 40 formed adjacent the uppermost edge thereof and spaced from such end that bears against the innermost face of panel 12. This said end of member 28

passes through an opening 42 formed in the panel 12, and an out-turned flange 44 overlaps the outermost face of panel 12 for rigidly holding member 28 secured to panel 12.

A pair of opposed slots 46 formed in the member 28 adjacent the innermost end thereof have their longitudinal axes substantially parallel with longitudinal axis of member 28.

The dogs 48 extend through each of the slots 46, respectively, toward the innermost face of member 30. One of these dogs 48 (Fig. 3) is bifurcated as at 50 for receiving the other dog 48. Both of the dogs 48 are disposed within the bifurcated end 52 of an elongated rod 54. The pivot pin 56 passing through the bifurcated end 52 of rod 54 and through both of dogs 48 swingably mounts these dogs 48 on the lowermost end of rod 54.

Rod 54 is disposed coaxially within the member 28 and has secured in the uppermost end thereof a button 58 by means of a pin or the like 60. This button 58 is preferably circular in cross sectional contour and has an out-turned flange 62 formed thereon that abuts against an inturned flange 64 formed at the uppermost end of member 28.

A spring 66 coiled about rod 54 bears at its uppermost end directly against the innermost face of button 58. Inturned projections 68 formed in the member 28 inwardly from the slots 46 thereof receive the lowermost end of spring 66. Each of dogs 48 has a flat portion 70 formed adjacent to the outermost free ends thereof that is substantially parallel to the transverse axes of members 28 and 30, presenting a relatively sharp outermost edge on both dogs 48 capable of biting into the innermost face of member 30.

It is clear from the foregoing that the spring 66 yieldably holds the rod 54 in the uppermost end of its reciprocal path of travel where the flange 62 of button 58 bears against the inturned flange 64. When rod 54 and button 58 are in such position, the dogs 48 will be projected through the slots 46 to a position where they tightly engage the number 30.

Any tendency of the panels 12 and 14 to move outwardly away from each other will be retarded, and, in fact, such outward movement will operate to wedge the post or dogs 48 more tightly against the member 30. This pair of opposed dogs 48 operates as a wedge between the member 28 and 30, since their combined action holds the rod 54 centered within the member 28 and the latter cannot shift outwardly because of slots 46 surrounded by respective body 48.

When it is desired to release the locking means, thereby permitting the movement of the panels 12 and 14 apart to a position where the same are entirely separated, the operator merely presses inwardly upon the button 58 against the action of the coil spring 66 swinging the dogs 48 on the pivot pin 56 and thereby moving the same out of biting engagement with the member 30.

Any number of these locking assemblies 26 may be utilized, but it is contemplated that only one is necessary for each binder 10.

As is clear in Fig. 1, the locking assembly 26 is disposed back of a pack of loose leaves 72, disposed between the panels 12 and 14. Such leaves 72 are provided with the usual perforations 74 for receiving connecting posts 76 and 78. As shown, these posts 76 and 78 are relatively telescoped, permitting expansion of the binder 10 for receiving a selected number of leaves 72.

Obviously, any of the well-known structures may be used for holding the leaves of paper 72 in place other than that illustrated in Fig. 1.

It is, also, clear that the locking assembly 26 permits such expansion of the binder 10 irrespective of the particular type of holding means for the leaves of paper themselves.

Fig. 4 of the drawing shows another way of mounting and forming the swingable locking dogs of the assembly. This form will operate equally as well as that illustrated in Fig. 3, but it is simpler and less expensive to manufacture. The dogs 100 and 102 shown in Fig. 4 are identical and, rather than one of these dogs being bifurcated, both are mounted directly upon a rod 104, one end of which at least is polygonal in cross section. Dogs 100 and 102 are disposed in opposed relationship with respect to the rod 104 and joined thereto by a common pivot pin 106.

Fig. 5 of the drawing shows another way of mounting a push-button for actuating the rod supporting either dogs 48 or dogs 100 and 102, as the case may be. The push-button in Fig. 5 is designated by the numeral 200; is circular in cross section and elongated. The inside diameter of a post 202, which corresponds to the member 28 of Fig. 2, is substantially the same as outside diameter of push-button 200, the latter being freely telescoped within the tubular post 202.

Post 202 is provided with a continuous annular out-turned rib 204 that corresponds with rib or shoulder 40 in Fig. 2 and, also, has an inturned flange 206 spaced from the out-turned rib or flange 204. Push-button 200 is provided with an annular groove 208 intermediate the ends thereof for receiving the inturned flange 206 of member 202.

Push-button is secured at its lowermost end directly to one end of a rod 210 corresponding to rod 54 of the modification shown in Fig. 2 of the drawing. It is clear that the width of the annular groove 208 in push-button 200 determines the extent of movement of push-button 200 and of the rod 210. A very small amount of such movement is necessary to release the dogs 48 or 100 and 102 with respect to the outermost tubular member 30.

While the above description of the various forms of the locking assembly has pointed out the use of such assembly with a binder such as at 10, it is contemplated that the members 28 and 30 may well be used to support the sheaf of loose leaf papers 72 in lieu of the telescoping posts 76 and 78. In other words, the outside diameter of the larger post 30 might well be less than the diameter of the perforations 74 in the leaves of paper 72 and no other means for holding paper 72 within the binder 10 will be needed.

It is, also, to be understood that the locking assembly might well be used without the utilization of binder 10 for holding the leaves of paper 72, if desired. In other words, if the outside diameter of the tubular member 30 is made sufficient to receive the perforations 74 of the paper 72, then such paper 72 might well be threaded upon the member 30 and shoulder 34, or like means, thereof will serve for limiting the movement of such ream of paper 72 beyond one end of the assembly. By the same token, the out-turned flange 40, or similar means, as at 204 in Fig. 5 of the drawing, will hold the opposite face of the ream of paper 72 against movement from the assembly.

Manifestly, many details of construction may be varied and such changes as fairly come with-

in the scope of the appended claims are contemplated hereby.

Having thus described the invention, what is claimed as new and desired to be secured by Letters Patent is:

1. For loose leaf binders having a pair of opposed backing panels movable toward and away from each other; manually releasable means for holding said panels against separation comprising a tubular member on each panel respectively, one of the members being slidably telescoped in the other member and having a pair of opposed openings adjacent the innermost end thereof; a reciprocable rod in said one member having a head extending beyond the opposite end of the one member, said head having an annular groove; an inwardly facing shoulder on the head; inturned ears integral with said one member between said openings and said opposite end thereof; a spring coiled about the rod and having the ends thereof bearing against said ears and said shoulder for holding the rod biased in one direction; an inturned bead on the one member extending into said groove for limiting the extent of movement of the rod in either direction; and

5 means on the innermost end of the rod and extending through each of said openings respectively for movement to and from a position engaging the other member as the rod is reciprocated.

2. Structure as set forth in claim 1 wherein the inside diameter of the other member is greater than the outside diameter of the one member, presenting a space between the members, 10 both of said means traversing said space, said other member being provided with an inturned flange on one end thereof for slidably receiving the one member.
